UNITED STATES PATENT OFFICE.

ARCHIE FRANKLIN MORAY, OF CEDARS, QUEBEC, CANADA, ASSIGNOR TO WESTINGHOUSE ELECTRIC & MANUFACTURING COMPANY, A CORPORATION OF PENNSYLVANIA.

VOLTAGE-REGULATOR.

1,303,360.

Specification of Letters Patent.

Patented May 13, 1919.

Application filed August 21, 1914. Serial No. 857,886.

To all whom it may concern:

Be it known that I, ARCHIE FRANKLIN MORAY, a subject of the King of Great Britain, and resident of Cedars, Province of Quebec, Canada, have invented certain new and useful Improvements in Voltage-Regulators; and I do hereby declare that the following is a full, clear, and exact description of the same.

10 This invention relates to regulators whereby the voltage of a circuit is raised or lowered, by an excitation circuit, proportionately to the increase or decrease in load.

It has been found that, when trouble, due 15 to short circuits, grounds, etc., develops on a system and a heavy flow of current and a drop in voltage occur, the present regulators, without there being any increase in load, excite the field circuit of the generator 20 in an effort to compensate for the reduced voltage, with the result that, when the trouble is cleared, the excitation current produces destructive voltages on the circuit for the reason that the excitation current does 25 not fall immediately but takes a few seconds to do so.

The over-excitation of the circuit without an increase in load results in damage to insulators, transformers and other apparatus 30 and an object of this invention is to prevent over-excitation of the generator fields when short circuits, grounds or other troubles occur on the system and, in this way, prevent high-voltage surges when the trouble is 35 cleared.

The above, with further objects and advantages, will be hereinafter more fully described and particularly pointed out in the claims.

40 For full comprehension, however, of my invention, reference should be had to the accompanying drawing forming a part of this specification in which similar reference characters indicate the same parts and 45 wherein the installation of my improved regulator is illustrated.

In the drawing, I have shown a voltage regulator employed in connection with an alternating-current circuit 2 and a generator 50 at 2^a, such regulator comprising an alternating-current magnet 3 and a direct-current magnet 4.

The magnet 3 is provided with a dashpot 3^a and its winding is connected across the 55 generator mains through a transformer 5.

Its plunger or movable core member 7 is attached to a lever 8 that is pivoted at 9, a counterweight 14 being suspended therefrom to assist in bringing the lever and plunger to a point A of equilibrium, and a contact member 10 being carried thereby. The magnet 4 is connected across the mains of an exciter 6, its plunger or movable core member 11 being attached to one end of a pivoted lever 12, the opposite end of which carries another contact member 13 that cooperates with the member 10. The pull of magnet 3 is opposed by a spring 14^a and the pull of magnet 4 by springs 14^b.

A relay magnet winding 32 is connected 70 to the exciter mains, and, as shown at 34, a shunt circuit thereto is opened and closed by the main contact members 10 and 13. The relay magnet is provided with a pivoted armature 33 that, in its vibrations, controls the effective value of a resistance 36, as included in the field circuit of the exciter. As other relay magnets similar to magnet 32-33 may be employed if required, additional terminals 35 are provided for 80 connecting such additional relays to the resistance 36. When the load on the circuit 2 increases, the voltage of the circuit decreases and the pull of the magnet 3 is thereby reduced. The plunger 7 of the coil 85 3 is accordingly lowered, thereby causing the contact member 10 to approach the contact member 13. The contact member 13, which is carried by the lever 12, is vibrated into and out of engagement with the terminal 10, due to the fluctuations of the exciter voltage, and, by reason of the raising of the contact member 10, the voltage of the exciter is increased and the field of the generator 2^a is strengthened.

95 The foregoing briefly describes the well known Tarrill regulator wherein the alternating-current voltage is regulated indirectly by rapidly opening and closing a shunt circuit across the exciter field rheostat, thus varying the exciter voltage in order to maintain the desired alternating-current voltage.

The disadvantage of this regulator is that, even without an increased load on the main 105 circuit, when trouble due to short circuits, grounds, etc., develops on the system there is always a heavy flow of current and drop in voltage to which the regulator responds and acts to over excite the generator field,

and, as it takes some seconds for the excitation to fall after the trouble has been cleared and, as there is no increase in load, such tardily falling excitation causes destructive voltages on the alternating-current circuit which damage insulators, transformers and other apparatus.

The main feature of the present invention is the application of an attachment to the above described voltage regulator which, while permitting the regulator to operate in the usual manner upon an increase in load, at the same time prevents overexcitation of the generator field when short circuits, grounds, etc., occur and thereby also prevents high-voltage surges when the trouble is cleared.

To secure the above mentioned advantageous result, lever 8 is provided with an extension 15 that is disposed beneath and in the vertical path of a movable pin or projection 16, the position of which is controlled by solenoids 17 and 18. It is preferred to have such pin mounted upon and carried by one of the cores 19 of the solenoids 17 and 18, such cores being linked together at the top by a bar 20 pivoted at 21.

The solenoids are controlled by a "Kelvin"-balance wattmeter comprising two pairs of fixed coils 37, 38 and 39, 40 and movable coils 41 and 42 that are located between the fixed coils and are mounted upon a lever 43 having a pivot at 44. The movable coil 41 is provided with a contact member 45 located between stationary contact members 46 and 47 that are respectively connected to terminals of the solenoids 17 and 18. A lead 48 from the solenoids 17 and 18 and a lead 49 from contact member 45 are brought to terminals 50 and 51 which are supplied from either an alternating or direct-current constant potential circuit such, for instance, as from a battery. The coils 37, 38 and 39, 40 are connected by wires 23 so as to be controlled by all circuits leaving the generator station. The arrangement of the fixed and movable coils is such that, with an increase in the power in the circuit, the coil 41 is repelled by coil 37 and attracted by coil 38 and, at the same time, coil 42 is repelled by coil 40 and attracted by coil 39, the contact member 45 being thus forced against the member 47, while, when the power decreases, a spring 54, that is interposed between the levers 20 and 43, forces the contact member 45 against contact member 46. When trouble occurs and the power factor of the system decreases and the voltage drops, the wattmeter reads low and moves the contact member 45 against contact member 46, thus energizing solenoid 17 and causing the core thereof and pin 16, which is carried thereby, to move downwardly. The pin 16 engages the extension

15 of the lever 8 and moves it downwardly from position A against the influence of magnet 3 to raise it, to lower the excitation of the station. The more pronounced the trouble the lower the excitation will become, until the lever 8-15 is forced down to "no-load" position, as shown by dotted lines at B, and when the fault on the system is cleared, the alternating current voltage will rise to its "no load" value until such time as the load is built up again at the station. In the same way, when the wattmeter, responding to the variations in voltage of the alternating-current circuit, reads high, the contact 45 will be moved against contact 47 to energize solenoid 18 and raise pin 16, lever 8-15 being thus permitted to be raised to "full-load" position C for the excitation of the generator fields.

The regulator can control, within a limited range, the voltage independently of the wattmeter, as the lever extension 15, being below pin 16, is capable of being moved through the influence of the regulator alone within the range of positions A and B.

In order to prevent the station voltage rising, due to heavy currents alone, contact-making ampere meters 30 are installed between the feeding circuit and the watt-meter.

The ampere meters are illustrated diagrammatically and are so adjusted that, at a predetermined current passing through the power circuit, the position of the pointer 52 is such that it makes contact, the current taking the path of least resistance, that is, through the pointer, that portion of the circuit connected with the current coils of the wattmeter being thus short circuited. This short circuiting of the wattmeter coils causes the wattmeter to read zero and, therefore, the regulator must give "no-load" excitation or lower if the regulator has been properly adjusted.

This attachment also prevents high voltage, due to failure of connections to the regulator, for the reason that, if the circuit is interrupted on the alternating-current magnet 3, lever 8-15 cannot rise, owing to pin 16, unless load comes on and, furthermore, my attachment prevents the jumping action of regulators when paralleling alternating-current generators.

What I claim is as follows:

1. In combination, a generator, a main circuit supplied by the generator, an exciter circuit for the generator, a regulator connected to the main circuit for regulating the voltage of the exciter circuit, a wattmeter connected to the main circuit and adapted to control the regulator, and means responsive to a function of the energy delivered for controlling a circuit of the wattmeter.

2. In combination, a generator, a main

circuit supplied by the generator, an exciter circuit for the generator, a regulator connected to the main circuit for regulating the voltage of the exciter circuit, a wattmeter connected to the main circuit and adapted to control the regulator, and a contact-making ampere meter for at times short circuiting certain of the coils of the wattmeter.

3. The combination with an electric circuit, and a dynamo-electric machine associated therewith, of a regulator for varying the field excitation of the dynamo-electric machine having a lever, a member normally permitting free movements of the said lever and adapted, under certain conditions, to limit the said movements, means for actuating the said members, means responsive to the power traversing the said circuit for controlling the said actuating means, means interposed between the said member and the said power-responsive means whereby the former exercises an influence upon the

latter, and means responsive to the current traversing the said circuit for controlling the power-actuated means. 25

4. The combination with a supply circuit, and means comprising a regulator for governing the electrical conditions of the supply circuit, of auxiliary means comprising a plurality of electromagnets having armatures loosely connected to said regulator, and a wattmeter connected to the supply circuit and serving to selectively energize said electromagnets for governing the operation of said auxiliary means in a manner to prevent the operation of the said regulator under abnormal supply-circuit conditions. 30

In testimony whereof, I have signed my name to this specification, in the presence of two subscribing witnesses.

ARCHIE FRANKLIN MORAY.
